ALBERT BROADMEYER, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA

VALVE MECHANISM FOR SUCTION FEEDERS

Application filed November 15, 1929. Serial No. 407,547.

In that type of sheet feeding apparatus in which a suction roller is employed for removing the sheets, and one or more blast nozzles are utilized for raising the top sheets to the suction roller, it is common practice to employ a single pump for creating suction in the suction roller and delivering the air to the nozzles. It is furthermore the custom to employ a controlling valve between the pump and suction roller that is periodically operated to open the suction between the roller and the pump, the air withdrawn through the suction roller being delivered to the nozzles. This valve when it is in closed position and therefore cuts off communication between the suction roller and the pump, opens a vent to atmosphere so that air may continue to be delivered from the pump to the nozzles. In the structure as now in general use, during the opening movement of the valve there is a period in which the air supplied to the pump is momentarily reduced and as a consequence the blast delivered through the nozzles is materially cut down. As a result the floating sheets are apt to drop away from the suction roller so that when the valve comes to open position and suction takes place through the suction roller, the sheet is not in the most desirable position to be quickly caught by the roller.

One of the principal objects of the present invention is to provide mechanism by which the valve is given a quick movement, so that the suction through the suction roller will occur quickly, and the sheet to be engaged and moved by the roller will be fully floated and in position to adhere to the suction roller.

In the accompanying drawings:

Figure 1 is a diagrammatic view showing the system in general use, but equipped with the preferred embodiment of the invention.

Figure 2 is a view in elevation and partially in section on an enlarged scale of the valve and its operating means with said valve in open position.

Figure 3 is a view similar to Figure 2, but showing the valve in section and locked in its closed position.

Figure 4 is a view similar to Figure 3, but

showing the valve in elevation and just about to be released.

Figure 5 is a cross sectional view on the line 5—5 of Figure 2.

Figure 6 is a detail perspective view of the valve.

Figure 7 is a longitudinal view through the valve and on an enlarged scale.

In the structure as disclosed schematically, in Figure 1, a pile of paper sheets 7 is supported on a table 8, and located thereover is a suction roller 9. These may be of the usual construction, in which the table is automatically elevated, as the sheets are removed by the roller. Leading from the roller 9 is a conduit 10 extending to the intake of a pump 11, and this pump has an outlet, to which is connected a pressure conduit 12 leading to one or more nozzles 13 that direct blasts of air against the upper rear portion of the paper pile to float the upper sheets upwardly to a position to be engaged and held by the roller 9. The roller then in its rotation carries the sheets rearwardly in a manner well understood.

In the conduit 10 is located the valve for controlling the passage of air from the suction roller 9 to the pump 11. This valve mechanism is designated generally by the reference numeral 14.

As shown a transversely disposed valve casing 15 is employed with oppositely disposed nipples 16 and 17 to which the sections of the conduit 10 are connected in the usual manner. These nipples have passageways 18 and 19 therethrough that are in alinement and are located on opposite sides of a valve chamber 20. In this valve chamber is a reciprocating plunger valve 21, tubular in form and having an annular channel 22 that is movable into and out of register with the passageways 18 and 19. When in register, as shown in Figure 2, the pump 11 is obviously in communication with the suction roller 9. When out of register, as shown in Figures 3 and 4, communication between the pump and suction roller is cut off. At this time, however, the passageway 19 is in communication with the atmosphere, inasmuch as there is a port 23 in communication with the passageway 100

19, this port opening into the bore 24 of the valve. More than that, a channel 25 formed in the underside of the valve leads from the port 23 to other transverse ports 26 formed in the exposed end of the valve. These various ports and passageways therefore afford ample space to supply the passageway 19, and consequently the pump 11 when the valve is in closed position. When the valve is 10 opened, however, then the supply of air to the pump 11 is brought from and through the suction roller 9, the periphery of which is open, as usual, so as to cause the topmost sheet of the pile 7 to be attached thereto, this 15 sheet having been elevated to the roller by the blast of air delivered from the nozzles 13.

For the purpose of operating the valve a power driven cam member 27 is employed mounted on a shaft 28 and slidably carried 20 by said shaft, and at one side of the cam member is a yoke 29 provided with a roller 30 operating in the cam groove 31 formed in the face of the cam member 27. The yoke 29 is connected to a rod 32 that slidably passes 25 through the bore 24 of the valve 21. This rod has fixed thereto an abutment collar 33 which strikes against the adjacent end of the valve and moves the valve to the left or to its closed position. A separate means, to- 30 wit, a coiled spring 34, abutted against one end of the valve casing 15 and against a nut 35 fixed to the end of the valve, serves to move the valve in the opposite direction, when the abutment collar 33 is withdrawn by 35 the movement of the actuating rod 32 to the right. The valve is held against rotary movement by a screw key 36 engaged in a longitudinal groove 37 formed in one side of the valve.

40 The valve after its movement by the cam and actuating rod is held in its closed position by a vertically reciprocating latch 38 mounted in a housing 39 carried by one side of the valve casing 15. The latch is urged 45 downwardly by a coiled spring 40 and its lower end is adapted to drop into the groove 22 when the valve is closed, as shown in Figures 3 and 4. It therefore holds the valve and permits the actuating rod 32 with its 50 abutment collar 33 to move to the right. The free end of the actuating rod 32 projects beyond the valve and has fixed thereto a bracket 41 on which is an actuating dog 42 that has a beveled rear end 43 adapted to ride under 55 a pin 44 on the latch. Therefore when the actuating rod 32 moves sufficiently to the right the latch 38 will be raised, releasing the valve and permitting it to move quickly to the right or to open position under the influence of the spring 34.

It is believed that the operation of the mechanism can now be made clear. The valve is reciprocated in timed relation. When it is 60 fully open, suction through the roller 9 will cause the topmost sheet of the pile 7 to be

attached in the usual manner and moved from off the pile. When the valve is closed, then suction through the suction roller 9 will be destroyed, but the pump continues to deliver a blast of air drawn through the above described ports and passageways of the valve, so that the uppermost sheets will be floated and the top sheet brought up into close proximity or against the underside of the suction roller 9. If the valve moved to the right 75 slowly there would be a period when the initial suction would be weak and the blast of air through the nozzle 13 would be cut down. But with the present structure when the valve is closed by the cam, it is locked in closed position and the actuating mechanism moves away so that the valve is freed therefrom until the dog 42 raises the latch whereupon the valve almost instantaneously moves to its open position, full suction is immediately 80 created through the roller, and the full blast of air remains on the sheets.

In further explanation of the operation, attention is called to Figure 3. The portion of the cam groove in the angle A of cam 27 is just of the proper drop to smoothly move the rod 32 when the same is operated at a great speed. As the plunger 21 would be directly connected to 32, the suction line would be gradually opened and in this case the sheet would be blown against the suction roller, (sometimes this happens and other times not) and the sheet would be picked up by a small amount of vacuum and brought forward by the movement of the suction roller, thus bringing the sheet out of time with the gate, that is, ahead of time. This is particularly noticeable when longer sheets are fed and when the surface speed of the suction roller is increased. In the present improvement, the full amount of vacuum, no matter what vacuum the pump is set for, is brought into the suction roller line and the sheet is held by the suction roller and is fed forward. Angle "B" is the suction period which is long enough to bring the sheet in contact with other forward feeding elements such as intake rollers, etc. (not shown). The trip 38 is released just before angle "A" of the cam 27 has reached the lowest position. During the suction period of angle "B", the blast will decrease somewhat, depending on the amount of vacuum for which the pump is set, but only for a brief period. It will blow again full force as soon as this period is over.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention.

What I claim is:

1. In sheet feeding apparatus, the combination with a support for a pile of sheets, of a suction device for removing sheets from the pile, a nozzle for delivering a current of air to the pile to elevate the top sheets for action on by the suction device, an air pump, a conduit connecting the suction device and nozzle and including the pump, to cause the pump to withdraw air from the suction device and deliver air through the nozzle, a valve casing in the conduit, a valve in the valve casing movable between a position to close the conduit and a position to open it, mechanism for periodically moving the valve to one of said positions, and means for automatically freeing the valve from said operating mechanism and causing it to move from said position to its other position independently of the operating means.

2. In sheet feeding apparatus, the combination with a support for a pile of sheets, of a suction device for removing sheets from the pile, a nozzle for delivering a current of air to the pile to elevate the top sheets for action on by the suction device, an air pump, a conduit connecting the suction device and nozzle and including the pump, to cause the pump to withdraw air from the suction device and deliver air through the nozzle, a valve casing in the conduit, a valve in the valve casing movable between a position to close the conduit and a position to open it, mechanism for periodically moving the valve to its closed position, and means for automatically freeing the valve from said operating mechanism and causing it to move from said position to its open position independently of the operating means and at a higher rate of speed than that by which it is closed.

3. In sheet feeding apparatus, the combination with a support for a pile of sheets, of a suction device for removing sheets from the pile, a nozzle for delivering a current of air to the pile to elevate the top sheets for action on by the suction device, an air pump, a conduit connecting the suction device and nozzle and including the pump, to cause the pump to withdraw air from the suction device and deliver air through the nozzle, a valve casing in the conduit, a valve in the valve casing movable between a position to close the conduit and a position to open it, mechanism for periodically moving the valve to its closed position, means for holding it in its closed position, operating means other than said actuating mechanism for moving the valve to open position, and means operated by the actuating mechanism to effect the release of the valve by its holding means and permit it to be quickly opened by said operating means.

4. In valve apparatus, the combination with a fixed valve casing, of a valve therein

movable between an open position and a closed position, separate movable actuating means for respectively moving it to said positions, and mechanism for causing the different means to alternately operate the valve.

5. In valve apparatus, the combination with a fixed valve casing, of a valve therein movable between an open position and a closed position, separate movable actuating means for respectively moving it to said positions, a device for holding the valve after its movement to one position by one actuating means, and movable means for releasing the valve from the holding means to permit its movement by the other actuating means.

6. In valve apparatus, the combination with a fixed valve casing, of a valve therein movable between an open position and a closed position, separate movable actuating means for respectively moving it to said positions, a device for holding the valve after its movement to one position by one actuating means, and means moved by said first actuating means on its movement for releasing the valve from the holding means to permit its movement by the other actuating means.

7. In valve apparatus, the combination with a fixed valve casing, of a valve therein movable between an open position and a closed position, a movable power operated device for moving the valve to one position, a spring for moving the valve to the other position, a latch for holding the valve by the spring after its movement by the power operated device, and movable means for operating the latch to release the valve and permit its actuation by the spring.

8. In valve apparatus, the combination with a fixed valve casing, of a valve therein movable between an open position and a closed position, a movable power-operated device for moving the valve to one position, a spring for moving the valve to the other position, a latch for holding the valve by the spring after its movement by the power-operated device, and a movable latch operating device moved by the power-operated device on its movement and operating the latch to release the valve and permit its actuation by the spring.

9. In valve apparatus, the combination with a fixed valve casing, of a valve therein movable in opposite directions between an open and a closed position, one movable means for moving the valve in one direction, another means for moving the valve in an opposite direction, means for locking the valve temporarily after its movement by the one means to temporarily hold the valve and permit the first means to become free therefrom, and means movable to a position to thereafter release the valve to permit its movement in the other direction by the other means.

10. In valve apparatus, the combination

with a fixed valve casing, of a valve therein movable in opposite directions between an open and a closed position, one movable means for moving the valve in one direction, another means for more rapidly moving the valve in an opposite direction, means for locking the valve temporarily after its movement by the one means to temporarily hold the valve and permit the first means to become free therefrom, and movable means for thereafter releasing the valve to permit its movement in the other direction by the other means.

11. In valve apparatus, the combination with a fixed valve casing, of a valve therein movable in opposite directions between an open and a closed position, one movable means for moving the valve in one direction, another means for more rapidly moving the valve in an opposite direction, means for locking the valve temporarily after its movement by the one means on its movement to hold the valve and permit the first means to become free therefrom, and a device operated by that first means and moving to a position to operate the latch and release the valve and permit the valve's movement in the other direction by the other means.

12. In valve apparatus, the combination with a valve casing and a reciprocating valve therein, of a reciprocating actuating device engaging the valve to move it in one direction and having an independent movement in the other direction, another actuating device for moving the valve in said opposite direction to a point to be reengaged by the first device, a latch for temporarily holding the valve against the latter movement to permit the independent movement of the first actuating device, and means for operating the latch.

13. In valve apparatus, the combination with a fixed valve casing and a reciprocating valve therein, of a reciprocating actuating device engaging the valve to move it in one direction and having an independent movement in the other direction, another actuating device for moving the valve in said opposite direction to a point to be reengaged by the first device, a latch for temporarily holding the valve against the latter movement to permit the independent movement of the first actuating device, and means operated by the first actuating means and movable to a position to operate the latch and release the valve to the action of the second actuating device.

14. In valve apparatus, the combination with a valve casing, and a reciprocating valve therein, of a reciprocating actuating device engaging the valve to move it in one direction and having an independent movement in the other direction, a spring for moving the valve in said opposite direction to a point to be reengaged by the first device, a latch for temporarily holding the valve against action

by the spring to permit the independent movement of the first actuating device, and a latch operating device.

15. In valve apparatus, the combination with a valve casing and a tubular reciprocating valve therein movable in one direction to an open position and in an opposite direction to a closed position, of a reciprocating actuating rod slidable in the valve and having an abutment to engage the same and move it in one direction, said rod being independently movable in the opposite direction, a spring for moving the valve in an opposite direction, a latch that engages the valve after its movement by the rod to hold it against opposite movement by the spring, and a trigger operated by the rod and operating the latch on the return movement of the rod to release the valve and permit its movement by the spring.

In testimony whereof, I affix my signature.

ALBERT BROADMEYER.
